COVER

Robert W. Crosem, Jr., Plainfield, Ill., assignor to
 Farrell Manufacturing Company, Joliet, Ill., a
 corporation of Illinois

Application April 20, 1931, Serial No. 531,325

15 Claims. (Cl. 220—55)

This invention pertains to covers, and more specifically to cover plates adapted for use particularly with tanks used on tank wagons and the like.

5 It is an object of this invention to provide a simple, effective, yet inexpensive cover for tanks, hatches and the like which is positive in operation, is rugged of construction, and is easily operated.

10 Another object of the invention is to provide a cover for tank wagons and the like wherein the locking mechanism positively locks the cover in such position that it is tightly sealed, yet may be readily and easily released.

15 With these and various other objects in view, the invention may consist of certain novel features of construction and operation as will be more fully described and particularly pointed out in the specification, drawing and claims appended hereto.

20 In the drawing, which illustrates an embodiment of the device and wherein like reference characters are used to designate like parts—

Figure 1 is a top plan view of a hatch cover embodying the invention;

Figure 2 is a side elevation of the device shown in Figure 1;

Figure 3 is an enlarged sectional elevation of the hatch cover and adjacent parts, the same being taken substantially in the plane as indicated by line 3—3 of Figure 1; and

Figure 4 is a sectional elevation corresponding to Figure 3 of a modified form of hatch cover.

Referring first of all more particularly to the 35 movable cover, this cover comprises a plate 10 of any configuration in plan, such as circular, oval, etc. The cover is apertured adjacent the center thereof to receive the thimble 12 welded thereto as at 14, the thimble being threaded as

40 at 16 to receive a closing plug 18. The strong back 20 extends across the cover and embraces the thimble, preferably having an enlarged portion 22 adjacent said thimble, there being slight movement permitted between the strong back

45 and the thimble. The thimble is provided with a removable locking device 24 in the nature of a spring or keeper member adapted to be seated in the groove 26 provided in the thimble, and the strong back is spaced from the cover by means

50 of the plate 28 provided with the depending spring fingers 30 serving as a cushion between the strong back and the cover plate. It is to be understood that a composition may replace this metallic plate 28. The strong back is provided with a hinge butt 32 adapted to be pivoted as at 34 to

the L-shaped hinge butt 36 shown in Figure 3, or the upstanding hinge butt 38 shown in Figure 4.

In the construction shown in Figures 1 to 3 inclusive the hinge butt 36 is formed integral with, or secured to, the upstanding combing 40 welded or otherwise secured to the tank 42. The cover plate 10 is provided with an inner plate 44 secured thereto and conforming substantially to the contour thereof, the plates 10 and 42 being provided with spaced depending flanges 46 and 48 between which packing 50 is provided. The combing is provided with the substantially L-shaped upstanding standard or butt 52 formed integral therewith or secured thereto, to which the link 54 is pivoted as at 56. The link comprises spaced arms 58 connected and formed integral with the strap 60. The locking dog 62 is pivoted as at 64 to the link between the arms 58, the locking dog being provided with the operating handle 66 and the cam shoulder 68. The operating handle is spaced sufficiently from the cover and strong back to permit the handle to be readily grasped, the shoulder 68 being provided with the extension 69 preventing the handle from rotating toward the cover to too great an extent, the strap 60 providing an auxiliary stop.

In the construction shown in Figure 4 the combing 70 is of the sloping type, being provided with the flanged and reflanged portions 72 and 74 adapted to be secured to the riser 76 by means of the bolts or other connections 78, suitable packing 80 being provided between the riser and the combing. The hinge butt 38 is secured or formed integral with the combing 70, as is also the butt or standard 82. In this case the combing is formed with an inner flanged portion 84 forming a seat for the packing 50 secured as before between the flanges 46 and 48 of the members 10 and 44 making up the cover. In this case, as before, the link construction 54 and the locking dog construction 62 are similar to those described with respect to Figure 3.

In operation of both devices, assuming the cover to be in the position shown in Figures 3 and 4, it is only necessary to rotate the handle 66 in a counter-clockwise direction and the cam 68 will cause slight depression of the strong back, depressing the spring fingers 30 which permit movement of the cam to unlocking position. The locking dog 105 and the link 54 may then be rotated about the pivot 56 to a position totally out of engagement with the strong back, whereupon the strong back may be used as a handle or lever in rotating the cover plate to open position. Movement and op- 110

eration to a closed position are exactly the reverse of that described.

A tight seal is insured as the parts are so proportioned that movement of the locking dog to locked position slightly compresses the packing 50 between the combing and the cover plate construction whereby leakage or ingress of foreign matter is prevented.

It is to be understood that I do not wish to 10 be limited by the exact embodiments of the device shown, which are merely by way of illustration and not limitation, as various and other forms of the device will of course be apparent to those skilled in the art without departing from the 15 spirit of the invention or the scope of the claims.

I claim:

1. In cover mechanism, the combination of a 20 combing provided with a hinge butt, a strong back pivoted to said butt and extending across said combing, a cover member for closing the opening of said combing, a connection between said cover member and strong back, a standard carried by said combing and having a link pivoted thereto, and a locking dog pivotally mounted on said link having a cam adapted to engage said strong back to lock said cover in closed position, said connection having a resilient member 25 between said strong back and cover member.

2. In cover mechanism, the combination of a 30 combing provided with a hinge butt, a strong back pivoted to said butt and extending across said combing, a cover member for closing the opening of said combing, a connection between said cover member and strong back, a standard carried by said combing and having a link pivoted thereto, and a locking dog pivotally mounted on said link having a cam adapted to engage said strong back to lock said cover in closed position, said connection having a resilient member 35 between said strong back and cover member, said cover member including a pair of plates, each of said plates having a depending flange, the space between said flanges having packing therein adapted to be seated on said combing when said dog 40 engages said strong back.

3. In cover mechanism, the combination of a 45 combing provided with a hinge butt, a strong back pivoted to said butt and extending across said combing, a cover member for closing the opening of said combing, a resilient connection between said cover member and strong back permitting yieldable movement therebetween, a standard carried by said combing and having a link pivoted thereto, and a locking dog pivotally mounted on said link having a cam adapted to engage said strong back to lock said cover in closed position, said cover member including a 50 pair of plates, each of said plates having a depending flange, the space between said flanges having packing therein adapted to be seated on said combing when said dog engages said strong back.

4. In cover mechanism, the combination of a 60 combing provided with a hinge butt, a strong back pivoted to said butt and extending across said combing, a cover member for closing the opening of said combing, a connection between said cover member and strong back, a standard carried by said combing and having a link pivoted thereto, a locking dog pivotally mounted on said link having a cam adapted to engage said strong back to lock said cover in closed position, said connection comprising a thimble secured to said cover member, said thimble having a stop thereon for 65 limiting relative movement between said cover member and said strong back, and a resilient

member between said strong back and said cover member for urging said strong back away from said cover member.

5. In cover mechanism, the combination of a 70 combing provided with a hinge butt, a strong back pivoted to said butt and extending across said combing, a cover member for closing the opening of said combing, a connection between said cover member and strong back, a standard carried by said combing and having a link pivoted thereto, a locking dog pivotally mounted on said link having a cam adapted to engage said strong back to lock said cover in closed position, said connection comprising a thimble secured to said cover member, said thimble having a stop thereon for 75 limiting relative movement between said cover member and said strong back, and a resilient member between said strong back and said cover member for urging said strong back away from said cover member, said cover member including a pair of plates, each of said plates having a depending flange, the space between said flanges having packing therein adapted to be seated on said combing when said dog engages said strong back.

6. In cover mechanism, the combination of a 80 combing provided with a hinge butt, a strong back pivoted to said butt and extending across said combing, a cover member for closing the opening of said combing, a connection between said cover member and strong back, a standard carried by said combing and having a link pivoted thereto, and a locking dog pivotally mounted on said link having a cam adapted to engage said strong back to lock said cover member in closed position, said connection comprising a thimble secured to said cover member, said thimble having a stop thereon for 85 limiting relative movement between said cover member and said strong back, said cover member including a pair of plates, each of said plates having a depending flange, the space between said flanges having packing therein adapted to be seated on said combing when said dog engages said strong back.

7. In cover mechanism, the combination of a 90 combing of rolled metal provided with a hinge butt, a strong back pivoted to said butt and extending across said combing, a cover member for closing the opening of said combing, a connection between said cover member and strong back, a standard carried by said combing and having a link pivoted thereto, and a locking dog pivotally mounted on said link having a cam adapted to engage said strong back to lock said cover in closed position, said combing including a flanged portion forming a seat for said cover member, and having a flanged and reflanged portion forming a securing seat.

8. In cover mechanism, the combination of a 95 combing provided with a hinge butt, a strong back pivoted to said butt and extending across said combing, a cover member for closing the opening of said combing, a connection between said cover member and strong back, a standard carried by said combing and having a link pivoted thereto, and a locking dog pivotally mounted on said link having a cam adapted to engage said strong back to lock said cover in closed position, said combing including a flanged portion forming a seat for said cover member, and having a flanged and reflanged portion forming a securing seat, said connection having a resilient member between said strong back and cover member.

9. In cover mechanism, the combination of a 100

- combing provided with a hinge butt, a strong back pivoted to said butt and extending across said combing, a cover member for closing the opening of said combing, a connection between 5 said cover member and strong back, a standard carried by said combing and having a link pivoted thereto, and a locking dog pivotally mounted on said link having a cam adapted to engage said strong back to lock said cover in closed position, said combing including a flanged portion forming a seat for said cover member, and having a flanged and reflanged portion forming a securing seat, said cover member including a pair of plates, each of said plates 10 having a depending flange, the space between said flanges having packing therein adapted to be seated on said combing when said dog engages said strong back.
10. In cover mechanism, the combination of a 20 combing provided with a hinge butt, a strong back pivoted to said butt and extending across said combing, a cover member for closing the opening of said combing, a connection between said cover member and strong back, a standard 25 carried by said combing and having a link pivoted thereto, a locking dog pivotally mounted on said link having a cam adapted to engage said strong back to lock said cover in closed position, said combing including a flanged portion forming 30 a seat for said cover member, and having a flanged and reflanged portion forming a securing seat, said connection comprising a thimble secured to said cover member, said thimble having a stop thereon for limiting relative movement between said cover member and said strong back, and a resilient member between said strong back and said cover member for urging said strong back away from said cover member. 35
11. In cover mechanism, the combination of a 40 combing provided with a hinge butt, a strong back pivoted to said butt and extending across said combing, a cover member for closing the opening of said combing, a connection between said cover member and strong back, a standard 45 carried by said combing and having a link pivoted thereto, a locking dog pivotally mounted on said link having a cam adapted to engage said strong back to lock said cover in closed position, said combing including a flanged portion forming 50 a seat for said cover member, and having a flanged and reflanged portion forming a securing seat, said connection comprising a thimble secured to said cover member, said thimble having a stop thereon for limiting relative movement between said cover member and said strong back, and a resilient member between said strong back and said cover member for urging said strong back away from said cover member. 55
- 60 said cover member including a pair of plates, each of said plates having a depending flange, the space between said flanges having packing there-
- in adapted to be seated on said combing when said dog engages said strong back.
12. In cover mechanism, the combination of a combing provided with a hinge butt, a strong back pivoted to said butt and extending across said combing, a cover member for closing the opening of said combing, a connection between said cover member and strong back, resilient means between said strong back and cover member and embracing said connection, a standard carried by said combing and having a link pivoted thereto, and a locking dog pivotally mounted on said link having a cam adapted to engage said strong back to lock said cover in closed position, said combing including a flanged portion forming a seat for said cover member, and having a flanged and reflanged portion forming a securing seat, said locking dog having an operating handle spaced from said cover member and means for preventing movement of said handle toward said cover member. 80
13. In a cover mechanism, the combination of a combing, a hinge butt, a strong back pivoted to said hinge butt and extending across said combing, a cover member for closing the opening in said combing, said cover member being secured to said strong back intermediate the ends thereof, resilient means disposed between said strong back and said cover member, and latching means cooperating with one end of said strong back for maintaining said cover member in closed position on said combing. 85
14. In a cover mechanism, the combination of a combing, a hinge butt, a strong back pivoted to said butt and extending across said combing, a cover member for closing the opening of said combing, a resilient connection between said cover member and strong back, latching means cooperating with said strong back for locking said cover member in closed position, said cover member including a pair of plates, each of said plates having a depending flange, the space between said flanges having packing therein adapted to be seated on said combing when said dog engages said strong back. 90
15. In cover mechanism, the combination of a combing provided with a hinge butt, a strong back pivoted to said butt and extending across said combing, a cover member for closing the opening of said combing, a connection between said cover member and strong back, a standard carried by said combing and having a link pivoted thereto, a locking dog pivotally mounted on said link having a cam adapted to engage said strong back to lock said cover in closed position, said connection comprising a thimble secured to said cover member and freely extending through said strong-back and said thimble having a stop thereon above said strong-back for limiting relative movement between said cover member and said strong back. 100
